UNITED STATES PATENT OFFICE.

INGWOLD G. JESNESS AND FREDERICK J. REICHLE, OF ST. PAUL, MINNESOTA, ASSIGNEES TO BROWN & BIGELOW, OF ST. PAUL, MINNESOTA, A CORPORATION OF MINNESOTA.

KEY CASE.

Application filed May 1, 1925. Serial No. 27,233.

Our invention relates to key cases and is particularly adapted to a simple key case wherein a series of keys are held on hook members and held so that they can be turned 5 out to select any key desired.

A particular feature of the invention is in providing a flexible hinge member formed of rawhide or other suitable flexible material which is common to all of the hook members which support the individual keys so that the rawhide member forms a common pintle for the key holding members. It is a very important part of the invention to provide this flexible pintle so as to provide 10 a pliable key case which when held in the pocket is not stiff and will flex in a manner to shape itself when bent to the ordinary use that a key case is subjected to in carrying the same in the pocket. This flexible 15 holding means for the key hooks provides a very practical means for supporting the same, yet the simplicity is quite apparent, thus providing a key case of an economical construction.

It is also a feature of our invention to provide a key case wherein the peculiar shape of the leather cover forms a feature in simplifying the manufacture and construction of the same. This formation of the cover includes the making of the same in a single piece of material, being cut, folded and shaped so as to provide a key case of the nature illustrated and described.

These features, together with other objects and peculiarities of the invention will be more fully set forth in the specification and claims.

In the drawings forming part of this specification:

Figure 1 is an illustration of our key case in closed position.

Figure 2 illustrates our key case open.

Figure 3 is a section on the line 3—3 of Figure 2.

Figure 4 illustrates the died out formation of our key case.

Figure 5 illustrates the flexible pintle holding means for key hooks.

Figure 6 illustrates one of the hooks.

In the drawings our key case A is made with a cover B of leather or any other suitable material, this cover is designed to form

a closure in which the keys are adapted to be held so that the keys are covered and may be carried in the pocket without injury to 55 the pocket.

The cover B is made from a single piece of material, and is provided with side flaps 10 and 11 which are folded upon the lines 12 and 13 respectively so that the flaps 10 and 11 overlap centrally over the back or body portion 14 of the case A when the same is folded.

The cover B is illustrated in died out formation in Figure 4 and is provided with 65 a central flap 15 which extends from the upper edge of the body portion 14 and extending from the center flap 15 is a flap 16 which is adapted to be turned over the flap 15 in a manner to form a pocket on the back 70 of the flap 15 in which an identification card can be placed, the flap 15 is folded on the line 17 and is sewed along the sides at 18 to form the closures for the side of the pocket 16. An eyelet 19 may be placed in 75 the lower portion of the flap 15 and extending through the flap 16. This eyelet may be used to attach the key case to a chain or other suitable holding means.

The cover B is formed with slots 20 approximately centrally disposed along the line 21 which divides the flap 15 from the back or body portion 14 and along the line 22 the flap is folded so that the flap 15 will lie centrally between the side flaps 10 and 80 11 and extend within the body of the case A.

The center flap 15 is folded along the line 21 and is sewed to the back 14 at 22 to form a recess extending along the sewing and with which the openings 20 communicate. We 90

provide key hooks 23 which are formed with eyes 24. By means of a raw hide pintle 25 or a flexible pin or rod of any suitable nature we attach the key hooks 23 to the key case A by placing the eyes 24 in the recess 95 through the openings 20 and inserting the pintle 25 when the eyes are in alignment. This is a very important part of our invention as it provides a simple means of assembling the key case and as the pintle 25 is 100 flexible and fits rather snugly in the opening formed by the sewing 22 the pintle is further held in place by frictional engagement with the eyes 24, thus attaching the hooks 23

and holding them in place in a manner to pivot about the pintle 25, to turn into position to be covered by the case B when in the position as illustrated in full outline in 5 Figure 2 or as to be turned out as illustrated in dotted outline in the same figure, so that when the keys are attached to the hooks 25 they are free to be moved in a 10 position to be enclosed by the cover B or turned out into position for use.

It is quite apparent that the simplicity of our key case is important in the manufacture and in the use of the same. After- 15 ward, if at any time the key hooks must be removed, this is accomplished very simply by pushing the pintle 25 out of engagement with the eyes 24 and lifting the hooks out of the openings 20, this provides a key case 20 wherein the holding means and hooks are removable, and it is possible to remove the hooks that are not desired for use.

Our key hooks 23 have a peculiar construction which we have designed to provide a practical hook for engaging the keys 25 to hold them against free disengagement, yet providing means that they can be removed when so desired. The loop 26 of the hook 23, which is formed of spring material, is provided with the tongue 27 which 30 extends toward the eye 24 and which is formed with an inturned end 28 which is adapted to lie under spring tension of the loop 26 against the back 29 of the hook. This inturned end 28 forms a hook end on 35 the tongue 27 which prevents the keys from disengagement from the hook 23. In attaching the key to the hook 23 the same is pressed between the back 29 and the inturned end 28, springing the same up suf- 40 ficiently to permit the key to slip under the inturned end 28, and thus into the loop 26. When it is desired to remove the key from the hook 23 the tongue 27 is lifted suf- 45 ficiently to remove the front from the back 29 and the key may be slid from under the inturned end 28. This particular construction of a hook is designed by us to be more adaptable to our key case and of a simple inexpensive construction.

50 While key cases have been designed heretofore of various constructions the particular formation and construction of our key case provides a holder for keys of a more flexible nature, economical to manufacture 55 and pliable, so that it can be carried in the pocket without having the objectionable rigidity as is apparent in other key cases.

In accordance with the patent statutes 60 we have described the principles of operation of our key case together with a particular formation, but we desire to have it understood that while we have shown

a certain form of our key case, this is only illustrative and we desire to have it understood that the invention can be carried out 65 by other means and applied to uses other than those above set forth within the scope of the following claims:

We claim:

1. A key case having a cover formed from 70 a single piece of leather and having a lateral extension from the body portion there- 75 of adapted to be folded over on said body portion and having slots formed in said cover at the line of fold between the cover and extension, sewing for holding the folded over portion adjacent the slots to form a horizontal recess, removable key hooks adapted to extend through said slots and a removable pintle adapted to extend 80 through said horizontal recess and engage said hooks to pivotally support the same.

2. A key case including a cover formed of 85 flexible material having a loop along one side thereof, a series of slots intersecting said loop, a series of key hooks adapted to extend into said slots, and a flexible fibrous pintle for supporting said hooks ex- 90 tending through said loop.

3. A key case including a cover, a loop 95 disposed in said cover, a flexible fibrous pintle situated in said loop, a series of slots in said loop and a series of key hooks suspended from said pintle extending through 100 said slots.

4. A key case having a cover formed from 105 a single piece of leather and having a lateral extension from the body portion there- 110 of adapted to be folded over on said body portion and having slots formed in said cover at the line of fold between the cover and extension sewing for holding the folded over portion adjacent the slots to form a horizontal recess, key hooks adapted to extend through said slots and a flexible 115 pintle adapted to extend through said hori- 120 zontal recess and engage said hooks to pivotally support the same.

5. A key case formed of a single piece of 125 flexible sheet material, a body portion, side flaps adapted to overlap and cover said body portion, a central flap extending from one end of said portion, a pocket flap extending from said central flap and adapted to be folded over and sewed thereto, said central flap being adapted to be folded over 130 and sewed to said body portion, a series of key hooks and a flexible member adapted to extend through the marginal hem formed by the sewing of the central flap to the body part to support said key hooks pivotally to said case.
